UNITED STATES PATENT OFFICE.

ROBERT G. KIRKWOOD, OF PITTSBURGH, PENNSYLVANIA.

HYDROCARBON-BURNER.

1,144,851.

Specification of Letters Patent. Patented June 29, 1915.

Application filed August 8, 1911. Serial No. 642,977.

To all whom it may concern:

Be it known that I, ROBERT G. KIRKWOOD, a citizen of the United States, residing at Pittsburgh, county of Allegheny, Pennsylvania, have invented certain new and useful Improvements in Hydrocarbon-Burners, of which the following is a specification.

The present invention relates to improvements in hydrocarbon burners.

10 The principal object of the invention is to provide a simple, compact, and efficient low pressure oil burner which will have a steady and constant velocity of air through a small nozzle supplied from a blower, as a blast 15 for atomizing and blowing the liquid fuel into the furnace; and also a supplemental supply of air through a larger nozzle which is supplied from the same source and having the same pressure and greater volume, 20 which may be controlled and regulated, or varied at will, without disturbing the atomizing blast, to an appreciable degree.

In existing forms of this class of burners, a prevailing objection is the impracticability of regulating the air for combustion without reducing the pressure and volume of air at the mouth of the nozzle and thus preventing the atomizing of the fuel oil. This is an essential feature in hydrocarbon 30 burners of this type, as frequently the occasion arises when the air supply must be regulated for a small fire, or small supply of oil. The oil then cannot be atomized as there is not sufficient air pressure at the end 35 of the nozzle and as a result the oil is forced in drops to the furnace, entailing waste in the fuel. I have produced a device which eliminates these objectionable features of this type of burner, overcomes difficulties in 40 its operation, and enhances the value of these burners to an appreciable extent.

With these objects in view the invention consists in a hollow casting in the form of a casing fashioned with a plurality of nozzles, an oil supply or feed pipe, an air blast pipe leading from a blower, and independent means for diverting and regulating the volume of air for combustion.

The invention further consists in certain novel features of construction and combinations of parts as hereinafter set forth in the specification and more specifically pointed out in the claim.

55 In the accompanying drawings I have illustrated one example of the physical embodiments of my invention constructed ac-

cording to the best mode I have so far devised for the practical application of the principles thereof, and which has proven highly satisfactory in practice. 60

Figure 1 is a vertical central sectional view of the burner applied to the front wall of a furnace. Fig. 2 is a vertical sectional view on line 2—2 on Fig. 1, and Fig. 3 is a longitudinal sectional view on line 3—3 65 Fig. 1.

As illustrated in the drawings the casing 1 is bolted by means of an annular flange 2, to the front wall 3 of a furnace, an opening 4 being present in said wall to accommodate 70 the open end or mouth of the nozzle 5, which is formed integral with the casing.

In addition to the large nozzle 5, a second and smaller nozzle 6 whose walls are projected from the material of the nozzle 5, is 75 cast integral with the casing. Both these nozzles taper and are somewhat restricted toward their open mouths, and an annular space 7 is formed around the inner nozzle. Preferably the nozzles are arranged concentric with each other to form a compact structure and provide efficiency in operating the burner. At a suitable point, in this instance the lower end of the casing, a tubular extension 8 is formed to provide a cylindrical 80 chamber 9 which chamber is in open communication with the chamber 7 of nozzle 5. A corresponding passage or chamber 10, merging with the interior of the inner nozzle 6 and opening into the chamber 9 at 85 point 11, is provided with the outwardly curved wall 12. At its lower end the extension 8 is enlarged, as at 13, to form an air inlet 14, and the extreme lower end of the extension is threaded for the reception of 90 the blast pipe 15 which is connected to a suitable fan or blower as a source of supply 95 for the burner.

The passage of the blast through chamber 14 is controlled and regulated by a gate 100 valve or damper 16 which is operable by a suitable wheel or other device, not shown. When this gate valve 16 is wide open, the air under pressure from the blast or blower, rushes into chamber 9 and is free to continue through opening 11, passage 10, and out through the open nozzle 6. In this manner the necessary blast for atomizing the liquid fuel is obtained.

To control and regulate the supply of air 110 for combustion to the burner, I employ a second gate valve 17 located in the chamber

9 and above the opening or orifice 11. By means of the hand wheel 18, (Fig. 3) as an exemplifying device, the gate valve 17 may be positioned to regulate the volume of air for combustion through the chamber 7 thus supplying the oxygen for combustion.

The liquid fuel is forced through an oil feed pipe 19 which is seated in an extension 20, and said pipe projects forwardly through 10 nozzle 6. An oil supply pipe 21, connected to a suitable supply, leads to chamber 22 bored in the extension 20 and the entrance of oil to feed pipe 19 is controlled and regulated by the needle valve 23 adapted to 15 act with the complementary valve seat 24 formed in the wall of the chamber 22. The usual valve stem 25, packing gland 26, and hand wheel 27 are employed in conjunction with the valve mechanism.

20 From the above description together with an inspection of Fig. 1 of the drawing, it is apparent that the blast for atomizing the liquid fuel is passed through the inner nozzle, and additional air is passed through the 25 outer nozzle, and the liquid fuel is passed through the feed pipe 19. The liquid fuel is atomized to an exceedingly fine spray by the air blast, and the mixed oil and air are further commingled as they emerge from 30 the open mouth of nozzle 5 and as fuel elements are forced into the furnace by the combined blast.

When starting the burner, the oil or liquid fuel from supply pipe 21, is regulated by 35 valve 23 and the air blast is supplied through pipe 15. The gate valve 16 is to be fully opened to permit the entire blast of eight or ten ounces to pass through the opening 11, chamber 10, and out through the

open mouth of nozzle 6, atomizing the liquid 40 fuel as it emerges from the end of the feed pipe 19.

The fuel supply and the air through gate 17 are regulated with relation to each other to produce desired combustion. For a more 45 intense fire a greater quantity of oil and a proportionately increased volume of air, giving larger supply of oxygen for combustion are necessary. In order to meet these requirements the oil valve 23 and the air 50 valve 17 are adjusted to proper position. In this manner the fuel elements may be varied and proportioned as desired.

From the above description it becomes obvious that I have produced a burner of this 55 type which fulfills the conditions set forth as the objects and purposes of my invention.

Having thus fully described my invention, what I claim as new and desire to cover by Letters Patent is:— 60

An integral casing formed with an inlet pipe having a valve therein, an outlet nozzle, and an outwardly curved back wall between these members, a blast nozzle in the outlet nozzle with walls projecting from the 65 wall at the rear of the outlet nozzle, and both nozzles having inlet openings in direct communication with the inlet pipe, a valve regulating the inlet opening to the outlet nozzle, and an oil feed pipe extended 70 through the blast nozzle.

In testimony whereof I affix my signature in presence of two witnesses.

ROBERT G. KIRKWOOD.
